LIQUID FUEL SUPPLY MECHANISM FOR
OIL STOVESDonald H. Lapointe, Meriden, Conn., assignor to
The Miller Company, Meriden, Conn., a cor-
poration of Connecticut

Application February 12, 1938, Serial No. 190,145

4 Claims. (Cl. 103—213)

The present invention relates to liquid fuel supply mechanism for oil stoves, and is more particularly directed toward supply systems for oil stoves adapted to elevate the liquid fuel from a low level supply tank to a reservoir above the level of the burners and to supply the fuel from this reservoir to burners.

The present invention contemplates an electrically operated pump by which fuel can be drawn up into a reserve chamber or reservoir from which it is fed down through suitable float valves so as to be supplied to the burners.

The accompanying drawings show, for purposes of illustrating the present invention, one of the many embodiments in which the invention may take form, it being understood that the drawings are illustrative of the invention rather than limiting the same.

In these drawings:

20 Figure 1 is a vertical sectional view taken on the line 1—1 of Figure 4 and illustrating diagrammatically the outflow pipes and connections;

25 Figure 2 is a front elevational view of an oil stove having burners at two levels;

Figure 3 is a top elevational view of the oil pump with the tank in section;

Figure 4 is a vertical sectional view on the line 6—6 of Figure 1;

Figure 5 is a fragmentary sectional view on the line 5—5 of Figure 1;

Figures 6 and 6A are diagrammatic views illustrating the operation of the gear train taken in the direction of the arrows 6 of Figure 4;

Figure 7 is an enlarged sectional view on the line 7—7 of Figure 4; and

Figure 8 is a section taken on the line 8—8 of Figure 7.

In Figure 2 a stove is illustrated having upper burners 10 adapted for cooking on top of the stove and lower burners 11 adapted for operating an oven. The burners 10 are connected by a pipe 12 with a fuel supply basin or tray 13, while the burners 11 are connected by a pipe 14 with a tray or basin 15. Fuel is adapted to be supplied to these basins by pipes indicated at 16 and 17, float valves 18 and 19 being employed to prevent flooding. The pipes 16 and 17 are connected into a reservoir 20 which may be made of sheet metal and placed in any convenient part 0 of the stove. A suction line is indicated at 21 and an overflow drain system is indicated at 22.

A supporting plate 24 is suitably secured across the top of the tank or reservoir 20. This plate carries a base plate or casting 25 for supporting 5 the operating mechanism for pumping the fuel.

This mechanism, as here shown, consists of a small electric motor 26 whose shaft 27 is disposed angularly with respect to a large driving gear 28. The shaft 27 carries a single tooth pinion 29 on its free end. This pinion is approximately spiral shaped, so that at any one time it can engage with only one of the teeth 30 of the large gear 28. In this manner a very great reduction in speed is obtained with a very simple mechanism. The circuit for the motor is under the control of a switch, indicated generally at 31, and this switch in turn is under the control of mechanism 32 operated by a float 33.

The gear 28 is mounted on a shaft 35 suitably secured in the casting forming the plate 15 25. The gear extends down into a well like portion 36 of this casting and carries cam members indicated at 37 and 38. These cam members receive a roller 39 carried on the downwardly extending end 40 of a lever 41 which is pivoted 20 at 42 to the casting 25. The cam acts to rock the lever 41 back and forth as the large gear 28 is revolved. The lower end 43 of the lever 41 is connected to piston rod 44 which operates the plunger 45 of a suction pump. The cylinder 46 25 of this pump, together with valve mechanism, indicated at 47, is suitably secured to a bracket arm 48 extending down from the upper part of the casting 25. This valve mechanism includes a ball check valve, indicated at 49, which is in 30 communication with the suction line 21 and a spring operated ball valve, indicated at 50, through which the fuel is discharged on the return stroke of the piston.

In operation the motor is controlled through 35 the switch which in turn is actuated by the float mechanism. When the motor operates to drive the pump fuel is drawn up through the suction line and is drawn up through the reservoir or tank 20 until the float mechanism closes 40 the switch. The fuel then runs down through the supply lines to the burners. The arrangement shown provides a convenient and effective mechanism with few moving parts for the purpose of pumping the oil into the reservoir, and also 45 makes it possible to use gravity feed for oil to burners at varying heights.

It is obvious that the invention may be embodied in many forms and constructions within the scope of the claims and I wish it to be understood that the particular form shown is but one of the many forms. Various modifications and changes being possible, I do not otherwise limit myself in any way with respect thereto.

What is claimed is:

1. A fuel pump for oil stoves comprising a tank, a frame plate secured across the top of the tank, an electric motor secured to the plate with its axis horizontal and spaced above the plate, a pinion carried by the motor shaft, a large gear rotatably carried by the plate and meshing with the pinion, a cam carried by the gear, a lever arm pivoted to the frame plate and having its upper end co-operative with the cam, a stationary pump cylinder, and a plunger disposed in the cylinder and operated by the lower end of the lever arm.

2. A fuel pump such as claimed in claim 1, wherein the motor shaft and the pinion axis are both horizontal but out of parallelism, the pinion is a single tooth spiral and the large gear has its teeth on the side facing the motor.

3. A fuel pump comprising a horizontal supporting plate having an upwardly opening gear receiving well, a gear in the well, a cam on the face of the gear, an electric motor secured to

the top of the plate and having a pinion in mesh with the gear to drive the gear, a lever arm pivoted to the lower part of the well and having its upper end extending over into the well, to engage the cam, the frame also having a downward extension, an inlet valve and pump cylinder secured to the extension, and a piston carried in the cylinder and connected to the lower end of the arm for actuation thereby.

4. In a fuel pump, an electric motor having a single tooth spiral pinion on the end of the shaft thereof, a cam gear mounted on an axis out of parallelism with the motor shaft but in a plane parallel with a plane through the motor shaft axis, the cam gear having peripherally disposed teeth extending from one face thereof to mesh with the spiral pinion, and a cam on the opposite face, a pump plunger operated from the cam, and a pump cylinder into which the plunger extends.

DONALD H. LAPONTE.
